HOUSING FOR A DOOR LIGHT

Lawrence W. Kasten, 4623 N. 24th Place,
Milwaukee, Wis.

Filed May 4, 1964, Ser. No. 79,810

Term of patent 14 years

(Cl. D48—20)

Fig. 1.

Fig. 2.

Fig. 3.

Fig. 4.

Fig. 5.

FIG. 1 is a perspective view of the housing for a door light;

FIG. 2 is a front side elevation thereof;

FIG. 3 is a top plan view thereof;

FIG. 4 is a right end elevation thereof;

FIG. 5 is a left end elevation thereof.

The rear side is a mirror image of the front side.

I claim:

The ornamental design for a housing for a door light, as shown and described.
